CLAIM

The ornamental design for an earbud case, substantially as shown and described.

DESCRIPTION

FIG. 1 is a perspective view of an earbud case, shown in a closed configuration, as seen from the top, right side and front;

FIG. 2 is top view thereof;

FIG. 3 is a left side view thereof;

FIG. 4 is a bottom view thereof;

FIG. 5 is a right side view thereof;

FIG. 6 is a front view thereof;

FIG. 7 is a back view thereof.

FIG. 8 is a perspective view of the earbud case of FIG. 1, shown in an open configuration, as seen from the top, right side and front;

FIG. 9 is top view thereof;

FIG. 10 is a left side view thereof;

FIG. 11 is a bottom view thereof;

FIG. 12 is a right side view thereof;

FIG. 13 is a front view thereof; and,

FIG. 14 is a back view thereof.

The dotted line portions of the drawings represent environmental structure only and do not form part of the claimed design.

1 Claim, 14 Drawing Sheets
